UNITED STATES PATENT OFFICE.

EDMOND C. HOWARD, OF NORFOLK, VIRGINIA.

DESIGN FOR A PHONOGRAPH-CABINET TOP.

57,907.

Specification for Design.

Patented May 17, 1921.

Application filed October 14, 1920. Serial No. 417,049. Term of patent 14 years.

To all whom it may concern:

Be it known that I, EDMOND C. HOWARD, a citizen of the United States, residing at Norfolk, in the county of Norfolk and State of Virginia, have invented a new, original, and ornamental Design for Phonograph-Cabinet Tops, of which the following is a specification, reference being had to the accompanying drawing, forming part thereof.

The figure is a perspective view of a phonograph cabinet top showing my new design.

I claim:

The ornamental design for a phonograph cabinet top as shown.

EDMOND C. HOWARD.
